OIL BURNING APPARATUS

Charles W. Whitney, Cambridge, and Axel Nelson, Boston, Mass., assignors, by mesne assignments, to Ellen T. Brennan, Cambridge, Mass.

Application April 2, 1931, Serial No. 527,120

3 Claims. (Cl. 158—86)

The present invention relates to improvements in oil burning apparatus, and more particularly to pilots for automatically lighting burners of this character when the fuel supply is open.

5 A familiar type of oil burner suitable for domestic purposes such as heating water and for adaptation to coal burning stoves and the like, comprises one or more circular oil grooves generally spaced in concentric relation and 10 mounted by perforated tubes which produce the familiar blue flame from the use of kerosene or furnace oil. In a common type of burner the oil supply is fed centrally to the head and is thereafter distributed to the circumferential grooves 15 by radiating conduits. The oil burning grooves may contain asbestos wicks which, upon saturation, facilitate the starting of the burner. Thereafter, upon heating of the tubes, the gas generated from the high temperature of the burner 20 is ignited above the wicks and produces the heat.

It is the object of the present invention to provide a constantly operating pilot which will serve to automatically light burners of this general type upon delivery of oil to the burner head, with a 25 resultant saturation of the wick. To this end it is proposed to provide a separate and independent supply of oil in proximity to each of the wicks located within an oil groove, and to burn this supply of oil with a blue flame to avoid coking or 30 charring. This is accomplished by providing a wick constantly immersed in the supply of oil from the pilot, and igniting it in proximity to a surrounding or partially surrounding hot tube, which avoids the formation of excessive carbon 35 deposits which would otherwise result in clogging of the burner. With this pilot in constant operation, delivery of oil supply in the manner to saturate the adjacent wick quickly ignites the oil with which the wick is saturated, the flame 40 traveling about the wick away from the pilot and starting the operation of the burner in the same manner as if ignited with a match or similar device. Where the burner is provided with more than one oil groove, it has been found desirable to 45 provide a separate and independent pilot in conjunction with each oil groove for separately igniting the grooves. Both of these pilots operate constantly and are continuously fed by a separate source of oil supply furnishing the requisite small 50 quantity of oil for the pilot.

In the accompanying drawing illustrating the preferred form of the invention, Fig. 1 represents a conventional form of burner in plan, with the improved pilot embodied therein; Fig. 2 is a side elevation of the head illustrating the oil supply

to the main burner and pilot; and Fig. 3 is a detail illustrating a section in elevation of the pilot tube with the oil supply thereto in the base of the burner head on the line 3—3 of Fig. 1.

5 The burner shown in the illustrated embodiment of the invention comprises generally a head casting 10, having an inner oil groove 12 and an outer oil groove 14 maintained in spaced and concentric relation, as is usual in this type of structure. The space within the inner groove and between the inner and outer grooves is available 10 for circulation of air to support combustion. The oil supply is fed centrally to the burner casting by a supply pipe 16, which communicates with outwardly radiating oil conduits 18 and 20 at their 15 point of intersection. These oil conduits furnish channels for conducting oil to the bottoms of the oil grooves. Lying in each oil groove is a wick 22, which serves to absorb oil fed thereto and maintain the wick saturated during the starting 20 of the burner. As will be evident to those skilled in the art, the oil supply is maintained in a fashion to maintain a constant level of oil with relation to the burner head and properly supply oil in a constant stream for initially saturating 25 the wicks and thereafter furnishing oil for combustion, this oil level being indicated by the dot and dash line in Fig. 3.

According to the present invention, a pilot basin 30 is formed in each of the oil grooves adjacent the bottom portion by building up the bottom of the groove, as indicated at 27. These two pilot basins are connected by an intercommunicating conduit 29, formed in a boss 30, to which oil is supplied through a pipe 32. Each of the basins 35 is surmounted by a perforated metallic sleeve 34, which serves as a hot tube after the pilot is started, and encloses a wick 36, the bottom of which is immersed in the pilot oil supply. The adjacent wick lying within the main oil groove 40 is broken, and opposite ends come into proximity with the pilot tube but are not in a position to be saturated by oil delivered to the pilot basin. The pilot is ignited and as soon as the surrounding sleeve becomes hot, a blue flame is maintained 45 which may be burned continuously without requiring any more frequent cleaning of the burner parts than is usual in burners of this character. With the pilot in operation, whenever it is desired 50 to start the main burner, the oil supply is merely turned on to deliver oil through the central delivery pipe, and the saturation of the wicks soon causes ignition of the oil adjacent to the pilot, the flame thereafter spreading away from the pilot 55 throughout the entire periphery of the wick.

Thereafter, the operation of the burner proceeds as in the case of oil burners of this type. The burner is extinguished by merely closing the main supply and allowing the pilot to continue its 5 operation.

It will be evident from the foregoing description and from an inspection of the drawings, particularly Figs. 1 and 3, that the pilot basins are in each individual instance completely isolated from the adjacent oil grooves so that the supply of oil to the pilot basin in each case is confined below the surrounding wall of the basin and is not allowed to seep over for the purpose of saturating the main burner wicks in the concentric grooves. The pilot flame burns within the perforated pilot sleeve in a manner to prevent any excessive accumulation of carbon, this flame being supplied with combustion air from about the outside of the burner and between 10 the concentric grooves, as will be evident to those skilled in the art.

From an inspection of Fig. 2 it will be noted that each pilot sleeve, so-called, consists of two oppositely disposed perforated legs 40, connected 25 at their upper ends as at 42. When these perforated pilots are in place and assembled with the concentric perforated sleeves 50, each of the members 34 forms, in conjunction with the inner and outer sleeves immediately adjacent thereto, 30 a pilot chimney or tube, as will be evident. It is desired to provide the members 34 at their lower ends with comparatively narrow elongated slots 52, which permit the pilot flame within the hot tubes to flare through the openings 52 and 35 ignite the surrounding vapor upon saturation of the main wicks.

It will be understood that this burner is provided with the usual perforated concentric tubes surmounting the burner base as is usual in burners of this character. It will also be employed with any conventional method of oil feed for delivering a continuous supply of oil to the grooves and a second and independent supply to the pilot or pilots.

45 What is claimed is:

1. A blue flame oil burner comprising a burner head having a main oil groove, flame directing partitions projecting upwardly from the edges

of the oil groove and having perforations to admit air into the space above the groove, a fuel pipe supplying oil to the burner, a pilot contained within the head adjacent the main oil groove for igniting the burner including a conduit separate from said fuel pipe supplying oil to the pilot wick when the burner is extinguished by exhausting the supply of oil to the oil groove, and metallic means separating the space immediately above the pilot from the rest of the 10 burner, said means being perforated to admit combustion air.

2. A blue flame oil burner comprising a burner head having a main oil groove, flame directing partitions projecting upwardly from the edges 15 of the oil groove and having perforations to admit air into the space above the groove, a fuel pipe supplying oil to the burner, a pilot contained within the head adjacent the main oil groove for igniting the burner including a conduit separate from said fuel pipe supplying oil to the pilot when the burner is extinguished by exhausting the supply of oil to the oil groove, and a perforated sheet metal means separating the space immediately above the pilot from the rest 20 of the burner, certain of the perforations adjacent the bottom end of the separating means being of sufficient size to permit the pilot flame to carry through and ignite vapor produced by the presence of oil in the main oil groove of 30 the burner.

3. A blue flame oil burner comprising a burner head having a main oil groove, flame directing partitions projecting upwardly from the edges of the oil groove and having perforations to 35 admit air into the space above the groove, a fuel pipe supplying oil to the burner, a pilot contained within the head adjacent the main oil groove for igniting the burner including a conduit separate from said fuel pipe supplying 40 oil to the pilot when the burner is extinguished by exhausting the supply of oil to the oil groove, and a perforated sheet metal means substantially shorter in height than the flame partitions separating the space immediately above the pilot 45 from the rest of the burner.
